UNITED STATES PATENT OFFICE.

ERNEST R. HUNTLEY, OF TOLEDO, OHIO, ASSIGNOR TO INDUSTRIAL RESEARCH CORPORATION, OF TOLEDO, OHIO, A CORPORATION OF DELAWARE.

VACUUM FEED SYSTEM.

Application filed April 7, 1920. Serial No. 372,046.

My invention relates to improvements in liquid fuel raising systems intended primarily for use in automobiles.

One of the objects of the invention is the provision of fuel raising apparatus, in which the necessity for an auxiliary fuel tank is eliminated.

Another object of the invention is the provision of a system in which the fuel is pumped up to the carburetor, but in which the moving parts of the pump do not come in contact with the fuel.

Another object is the provision of a float controlled valve for interrupting communication between the pumping cylinder and a pumping chamber through which the fuel flows, such communication being interrupted whenever the output of the pump exceeds the amount of fuel being used by the carburetor.

Other objects, and objects relating to details of construction and economies of manufacture, will appear as I proceed with the description of that embodiment of the invention, which, for the purposes of the present application I have illustrated in the accompanying drawings, in which—

Figure I is a longitudinal section of a casing in which are located the air cylinder and the float chamber of my pump, the casing including also parts of an oil pump for the supply of lubricant to the engine, the latter feature forming no part of the present invention.

Fig. II is a bottom plan view partially in horizontal section on the line II—II, Fig. I.

Fig. III is a view principally in vertical section taken substantially on the line III—III, Fig. I.

Fig. IV is a more or less diagrammatic view showing the invention as applied in connection with the engine of an automobile.

Similar reference characters refer to like parts throughout the views.

Referring first to Fig. IV, 10 indicates the main fuel tank of an automobile, from which leads the pipe 11 through which fuel is drawn by the pump, located at the side of a gas engine 12 preferably below the level of the carburetor 13 with which it is connected by the pipe 14. The oil pump lifts lubricant from a reservoir in the bottom of the crank case through pipe 15, and forces it through pipes 16 and 17 to the parts needing lubrication.

The structure of the fuel pump is shown in detail in Figs. I, II and III where 18 indicates the crank case of the engine, to which the casing of my pump is attached by means of machine screws 19, which pass first through holes in a flange 20 of the pump casing. The inner end of the latter is tubular and may extend inside the crank case for a distance to constitute a cylinder for a hollow piston 21, which is closed at its rear end and there provided with a bearing surface for engagement by a cam 22 fixed upon a shaft 23 driven by the engine. The oil pumping cylinder 24 is closed at its forward end by a partition 25 having a central elongated bearing 26 in which slides a rod 27 which is secured at its rear end to the closed rear end of the piston 21. A coil spring 28 bears at one end against said partition 25 and at the other end against the piston 21.

Depending from the forward end of cylinder 24 is a small chamber 29 having a nipple 30 threaded into the bottom thereof for attachment to the pipe 15. A ball check 31 seats itself in the top of the nipple 30 and is prevented by an inwardly extending arm 32 from rising too far off its seat. Extending laterally in opposite directions from the chamber 29 are the valve chambers 33 and 34, in which are located spring pressed ball checks 35 and 36. Suitably connected to the valve chambers are the pipes 16 and 17 through which the lubricant is fed to parts of the engine requiring it. One of the springs controlling the ball checks 35 and 36 may be of stiffer wire than the other in order to cause a lesser proportion of the oil to flow through one pipe than through the other, if this is deemed desirable.

Forward of the partition 25 the casing is formed to provide an air cylinder 37 which is closed at its front end by a threaded disk 38, the removal of which permits access to the cylinder. On the forward end of rod 27 is secured a piston 39 provided with bypasses 40 adapted to register through a peripheral groove 40' with a port 41 through the cylinder when the piston is at the forward limit of its motion. In the rear of the cylinder 37 is a small breather opening 42. On the lower side of the cylinder 37, and extending back from its forward end, there is grooved out a passage 43,

105

110

- the rear end of which communicates with a hole 44 through the cylinder, which hole connects the passage 43 with the interior of a float chamber or pumping chamber 45 which is preferably cast integral with the cylinder 37. The bottom of this chamber is a threaded disk 46 which has a central bore in its upper side constituting a guide for a valve stem 47, on the upper end of which is a conical valve 48. A float 49 is mounted upon the stem 47 and is adapted to raise the valve piece 48 to close the hole 44 when the level of liquid in the chamber reaches a predetermined height.
- 10   15   20   25   30   35   40   45   50   55   60
- 15   Into one side of the chamber a passage 50 opens. An upwardly opening inlet check valve 51 is mounted at the end of this passage and is adapted to prevent back flow of liquid after the latter has been raised into the chamber 45. Liquid enters the passage 50 through a nipple 52 to which is attached the pipe 11 leading to the fuel tank 10 (Fig. IV). A passage 53 leads from the other side of the chamber 45 to a valve chamber 54 in which is located an upwardly opening check valve 55. A nipple 56 is threaded into the casting above the valve chamber 54 and serves as a connector for the pipe 14 leading to the carbureter 13.

Operation.

The cam 22 rotating at a speed proportional to the speed of the engine drives the piston 21 and rod 27 to the left (Fig. I), while the spring 28 causes the return movement. The piston 21 on its suction stroke draws a charge of oil up through pipe 15, the ball checks 35 and 36 remaining seated. On the compression stroke the latter valves open and ball check 31 closes. The charge of oil is then forced outward through pipes 16 and 17 to parts of the engine needing lubrication.

40   45   50   55   60

45   At the same time the piston 39 is reciprocated. Assuming that the level of fuel in the pumping chamber 45 is not high enough to cause the float to actuate valve 48, then the hole 44 is open and on the suction stroke of the piston the air in chamber 45 is exhausted. Atmospheric pressure upon the fuel in tank 10 then causes fuel to rise in pipe 11, lifting valve 51 and flowing into chamber 45. At the end of the suction stroke, that is when the piston 39 is at the rearward limit of its motion, the front face of the piston recedes behind port 41 enabling air to rush in through that port and relieve the partial vacuum in the cylinder 37 and the chamber 45. The piston then begins to travel forward again closing port 41 and compressing the air above its head and above the liquid in chamber 45. This pressure, being transmitted through the liquid, lifts valve 55 and forces a charge of

fuel into pipe 14, and if the latter pipe be full enough then into carbureter 13. When the piston reaches the forward limit of its stroke, as illustrated in Fig. I, bypasses 40 and groove 40' connect the space in front of the piston and also the space in the pumping chamber above the liquid with port 41, which suddenly relieves the pressure in front of the piston and above the liquid in the chamber 45, thus preparing the apparatus for the next suction stroke. The operation continues in this manner until the level of liquid in the chamber 45 causes the float to raise the valve 48 and close the hole 44, whereupon the pressure in chamber 45 remains constant and the pumping action consequently ceases. At such times the air in chamber 45 will always be under pressure as there will undoubtedly be leakage of air around the valve 48 on the compression stroke, the pressure tending to unseat the valve. On the exhaust stroke, however, the valve tends to close even tighter, and therefore the pressure built up in the chamber 45 remains undisturbed. Now, as soon as further fuel is required by the carbureter its needle valve opens and permits the pressure in chamber 45 to force fuel up the pipe 14. The level in chamber 45 is thus lowered, and float 49 descends permitting valve 48 to descend and open the hole 44. Thus, the chamber 45 is subjected to the effect of the next suction stroke of the piston, whereby fuel is raised through pipe 11 into the chamber. In practice there will be a very small variation in the fuel level in chamber 45 and the suction stroke of the piston 39 will be made effective to draw fuel into the chamber 45 at fairly regular intervals, the frequency of which will depend upon the load upon the engine in proportion to its speed.

I am aware that the particular embodiment of my invention above described, and illustrated in the accompanying drawings is susceptible of considerable variation without departing from the spirit thereof, and therefore I desire to claim my invention broadly as well as specifically, as indicated by the appended claims.

I claim as my invention:

1. In combination, a pumping chamber having an inlet valve and an outlet valve for liquid to be pumped, a float in said chamber, an air cylinder closed at one end, a piston slidably therein, a connection between the top of said pumping chamber and said air cylinder, means for connecting the cylinder with atmosphere at times corresponding with both ends of the piston stroke, a valve controlled by said float for closing said first mentioned connection when the level of liquid in the pumping chamber reaches a predetermined height, a second cylinder connected to said air cylinder, a

pump within said second cylinder, and single means for operating said pump and said piston.

2. In combination, a casing, a pumping chamber in the bottom of said casing having an inlet valve and an outlet valve for liquid to be pumped, an air chamber in said casing above said pumping chamber, said casing having a passage connecting said chambers, means for producing compression and rarefaction alternately in said air chamber, a float in said pumping chamber, a valve controlled by said float adapted to close said passage, a liquid pump adjacent to said air chamber, single means for operating said liquid pump, and compression and rarefaction producing means in said air chamber.
3. In a liquid feed system, the combination of a chamber; a plurality of separated pistons axially movable in said chamber; means normally holding said pistons at one end of their movement and additional single means operated to displace the piston from normal end position; and float control means connected to said chamber adapted to control the pumping operation of one of the pistons.

4. In pumping mechanism, the combination of a two-part cylinder; interconnected pistons axially movable one in each section of the cylinder; single means for reciprocating said pistons; and a float controlled valve connected to one of said cylinder sections adapted to control the pumping operation thereof. 30

5. In combination, a pump cylinder; a piston axially movable in said cylinder; a second pump cylinder; a second piston movable in said second cylinder; means for reciprocating one of said pistons; and additional means for transmitting the reciprocation of said piston to the other piston. 35

6. In combination, a pump cylinder; a piston axially movable in said cylinder; a second pump cylinder; a second piston movable in said second cylinder; means for reciprocating one of said pistons; additional means for transmitting the reciprocation of said piston to the other piston; and float control means adapted to control the action 50 of one of said pistons.

In testimony whereof I affix my signature.

ERNEST R. HUNTLEY.
